UNITED STATES PATENT OFFICE

ARTHUR F. PYM, OF BEACH BLUFF, MASSACHUSETTS, ASSIGNOR TO SIBLEY-PYM CORPORATION, OF LYNN, MASSACHUSETTS, A CORPORATION OF MASSACHUSETTS

WINDING MACHINE

Application filed December 30, 1932. Serial No. 649,524.

This invention relates to machines for winding spherical cores, such as those used in the construction of golf balls, and its general object is to improve such machines in respect to the uniformity and accuracy of their operation under commercial conditions of use.

In the manufacture of golf balls, it is customary to employ a small core center of soft rubber or an acid-filled center and to wind upon this a tensioned elastic thread forming a spherical core of great resiliency. It is of the utmost importance to carry out the winding process symmetrically so that the core center shall at all times occupy the geometric center of the core and to arrange the windings so as to prevent displacement of the core center when the finished ball is subjected to the rough treatment incident to its use. In my prior application, Serial No. 507,816, filed January 10, 1931, I have disclosed a winding machine provided with a rotary detector member for detecting the zone of maximum diameter in the core as it is wound and reacting with the last wound turns upon the core to cause the latter to shift its position, thereby maintaining the core spherical in shape during the winding process. In one aspect the present invention consists in improvements in detectors of the type disclosed in said prior application. In another aspect it consists in improvements in winding machines in general tending to improve their accuracy in operation and sensitiveness in control of the position of the core.

I have discovered that by providing a rotary detector member with a covering which is transversely displaceable, I have provided a construction which satisfactorily meets all these requirements and, broadly considered, my invention consists in such an organized construction. In machines employing a rotary disk as a detector member, the displaceable covering may take the form of a circular shoe of rubber or other flexible material arranged to fit upon the disk in such manner as to partake of its linear travel and being at the same time free to slide sideways or laterally upon the disk

in reacting with the last wound turns of the core. Such a shoe, being of relatively small mass and so organized as to facilitate a temporary lateral displacement at the point of engagement with the core being wound, renders the core sensitive to surface irregularities and free for rotary shifting to establish a new winding zone and so tends to maintain the core in accurate spherical shape throughout the winding operation.

I have spoken of the displaceable covering as being freely movable transversely or laterally upon the detector and it should be noted that this movement is also transverse with respect to the winding zone determined by the thread guide which leads to the core being wound.

These and other features of the invention will be best understood and appreciated from the following description of a preferred embodiment thereof, selected for purposes of illustration and shown in the accompanying drawing, in which

Fig. 1 is a view in perspective of so much of the winding machine disclosed in my prior application, above identified, as is necessary to an understanding of the invention; and

Fig. 2 is a view, on an enlarged scale, partly in section, of the core supporting and rotating parts of the machine together with the rotary detector.

The driven elements of the machine are mounted in an upright frame 10, a portion of which is shown in Fig. 1. The frame is bored to receive a sleeve 12 in which are formed bearings for the main shaft of the machine to the outer end of which is secured a driving roll 14 which is somewhat concave in its cylindrical surface. The roll 14 constitutes the right-hand and driven roll of a horizontally disposed pair which support the core 100 which is to be wound. The left-hand roll 16 is similar in size but slightly convex in shape and is mounted to rotate idly upon the outer end of a stationary stud 18 projecting from the face of the frame 10.

As herein shown, an endless flexible band 20 is mounted upon the rolls 14 and 16, being

- driven by the roll 20 and acting to drive the roll 16. The core 100 to be wound rests in the bite of the upper pass of the band 20 as in a cradle, so that the band is the element which actually supplies support and traction for rotating the core. Since the band 20 is flexible, it wraps about a portion of the periphery of the core and imparts an impelling traction thereto, tending to obviate slip in the rotation of the core and being ample to rotate the core even under conditions involving severe tension in the elastic thread which is being delivered to and wound upon the core.
- 15 As the machine of my prior application, the rotary detector is carried by an arm 22 arranged to swing vertically about a horizontal axis and carrying at its free end a stationary transverse stud 24 which constitutes the journal of the detector. The detector, with the arm 22, is swung upwardly as the diameter of the core is increased and various operations in the cycle of the machine are controlled by this movement of the arm.
- 18 The detector is mounted for free rotation upon the stud 24 through the medium of ball bearings. As shown in Fig. 2, the inner race 26 is pressed upon the end of the stud 24 until it brings up against a shoulder formed in the stud. It is held in place by a screw 27 passing through a washer and being threaded into the end of the stud. The inner race provides for a double roll of balls and outside these is the outer race 26 which is pressed into the bore of the detector disk 30. Secured to the rear face of the disk 30 is a cover plate 32 and secured to the outer face thereof is a chambered cover plate 34. The two cover plates are held in place by transverse screws 36 which pass through the rear cover plate 32 and the disk 30 and are threaded into the outer cover plate 34. The chamber in the outer cover plate 34 provides an oil chamber which may be supplied through a centrally located oiler 38 in the cover plate. The detector disk itself has a circumferential rim which is convex in cross section. It will be apparent that the detector is arranged to spin freely as a unit upon the journal stud 24.
- 19 As a covering for the rim of the detector, I have disclosed herein a circular shoe 40 of rubber composition, preferably molded in a single piece to fit the convex periphery of the detector. The dimensions of the shoe 40 are such as to cause it to engage resiliently the rim of the detector about its central zone and, on account of the length of the contacting surfaces of the detector disk and the shoe, the latter will partake of the linear movement of the disk without any noticeable tendency to circumferential slipping.
- 20 The shoe 40 is inwardly concave in cross

section to fit the general contour of the convex rim of the detector disk 30 but its radius or curvature is somewhat longer than that of the contour of the rim, and it is provided with two circumferential flanges 75 which thus stand off somewhat from the sides of the rim of the detector disk. The result is that the shoe is free at all times to be displaced laterally or transversely upon the disk. A very light lateral impulse is 76 sufficient to cause such local displacement in the shoe 40, as, for example, at its point of contact with the core 100 in the winding zone of the latter.

Without undertaking to explain the complete phenomenon due to which the improved action of the detector of my invention results, it may be said that the shoe acts as a loose and easily displaced skin upon the rim of the detector. In cases where no 80 shoe of this kind is used, there must be at least a very slight friction between the last wound turns of the core and the metal surface of the detector rim. Where such a shoe as that herein shown is employed, friction 85 between the core and the shoe in the lateral displacement of the core is entirely obviated and the portion of the shoe which is in engagement with the core moves laterally with it. There is, of course, in this movement 90 some friction between the shoe 40 and the rim of the detector disk 30 but this may be reduced to a minimum by making the inner surface of the shoe of anti-frictional material or by lubricating the contacting surfaces of the two elements. The amount of friction effective to retard the transverse displacement of the core is reduced by this expedient materially as compared to that obtained in detector construction heretofore used, and the results are noticeably apparent 95 in an improved quality of core.

The effect above explained is doubtless increased or caused to some extent by the flexible nature of the shoe 40. While the lateral or transverse displacement of the small area of the shoe in actual engagement with the core is principally one of bodily displacement, a similar action results from a transverse elastic stretching of the material of the shoe.

As explained in my prior application, the band 20, which is carried by the rolls 14 and 16, is somewhat narrower than the length of the idle roll 16 and is thus permitted to sway laterally from side to side in response to lateral turning of the core brought about by the action of the detector. It will be seen that the core is thus supported between flexible and yieldable members which rotate the core and hold it in place during the winding process and that both of said members are mounted for temporary transverse displacement in reacting with the core.

The operation of the novel detector of my

invention will be clear from the foregoing description but may be summarized for convenience as follows. Having passed the end of the elastic thread about the core center, the operator lifts the detector arm 22 and places the core upon the endless supporting band 20, lowering the detector into contact with it. The machine is then set in operation and the mechanical winding operation initiated. As this continues, the detector arm is raised by the increasing diameter of the core and the detector is rapidly rotated by its engagement therewith. The winding zone is substantially vertical or transverse to the axes of the supporting rolls, being determined by a thread guide, not shown in the present drawing. The last wound turn or turns upon the core tend to create a surface projection, as indicated with some exaggeration in Fig. 2. This at once creates an unstable condition since the point of contact between the narrow ridge of the last wound turn and the detector is through the medium of the displaceable covering or shoe 40. The result is that as soon as any detectable ridge or oversize zone is formed in the core, the shoe reacts with this to shift laterally so that a new winding zone is produced in the core. This action is suggested in Fig. 2, from which it will be seen that the cross section of that portion of the shoe 40 which is in contact with the last turn upon the core is displaced slightly toward the left, with the result that the next turn to be wound upon the core will be located immediately to the right of the previous turn upon the side of the core now uppermost.

Having thus described my invention, what I claim as new and desire to secure by Letters Patent is:

1. A winding machine including means for supporting and rotating a core to be wound, a rotary detector member arranged to run on the periphery of the core and to react with the most recently wound turns thereon, and a transversely displaceable covering for the detector.

2. A winding machine including means for supporting and rotating a core to be wound, and a rotary detector mounted to turn on an axis parallel to the rotary axis of the core and having a loose covering arranged to slip transversely in reacting with the last wound turns on the core.

3. A winding machine including means for supporting and rotating a core being wound, a rotary detector having a convex periphery and being mounted to be rotated by engagement with the core, and a side-slipping contact element rotatable with the detector.

4. A winding machine including means for supporting and rotating a core being wound, a detector disk arranged to be rotated by engagement with the core, and an elongated flexible cover for the periphery

of said detector disk engaging the same in such manner as to partake of the linear travel thereof and being at the same time free to slide sideways in reacting with the last wound turns of the core. 70

5. A winding machine including means for supporting and rotating a core being wound, a detector disk, and a circular shoe of U-shaped cross section fitted upon the periphery of said disk in a manner to yield 75 locally and transversely.

6. In a winding machine, a detector disk having a hard polished surface, and a rubber circular shoe fitted loosely thereon and providing a transversely yieldable skin. 80

7. In a winding machine, a detector disk having a smooth hard surface, and a rubber circular shoe fitted thereon and having circumferential flanges which stand away from the sides of the detector disk and a U-shaped body portion enclosing the rim of the disk. 85

8. In a winding machine, a metallic detector disk having a convex rim, and a molded flexible shoe concave in cross section to fit the rim of the detector about its central zone and shaped to stand away from the sides of the rim, whereby the body of the shoe is left free for temporary lateral displacement in reacting with an object being wound. 90

9. A winding machine having rolls for engaging and rotating a core, a thread guide leading thereto and determining the winding zone therein, and a rotary detector mounted to engage the core at a point in its 100 winding zone opposite to said rolls and having a surface covering which is freely shiftable laterally with reference to the winding zone.

10. A winding machine having mechanism for supporting and rotating a core about an axis of fixed direction, a thread guide leading to the core and determining the winding zone therein, and a detector disk with convex rim mounted to rotate under the actuation of the rotating core and having a flexible surface covering which is interposed between said rim and the winding zone of the core and is carried with the disk 110 in its rotation and free to be temporarily displaced laterally with reference to the winding zone of the core. 115

11. A winding machine including oppositely-arranged flexible and yieldable members for rotating a core to be wound and holding it in place during the process, one of said members being mounted for free temporary transverse displacement in reacting with the core. 120

12. A winding machine including a driven flexible band for supporting and rotating a core to be wound, and a detector having a covering arranged for temporary displacement during the winding process in a 125 130

direction transverse to the linear travel of said core.

13. In a winding machine, a rotary detector having a flexible core-engaging covering which is free to stretch transversely during the winding operation.

14. In a winding machine, a rotary detector comprising an inner member having a convex rim and concentrically disposed ball bearings, and cover disks secured to its opposite faces of said inner member, one of said cover disks having an internal chamber registering with said bearings.

15. A winding machine including oppositely-arranged flexible members for rotat-

ing a core to be wound and holding it in place during the winding operation, both of said members being mounted for temporary transverse displacement in reacting with the core.

16. In a winding machine having a disk detector with a convex rim, a rubber circular shoe shaped to fit loosely upon the periphery of the disk, having a smooth, non-adherent inner surface adapted to slip freely thereon, being outwardly convex in cross section and having its free edges turned outwardly away from the surface of the detector disk.
